GLASS RACK

Bernard J. Zarzana and Roy T. Turner,
Whittier, Calif.

Application April 13, 1953, Serial No. 24,478

Term of patent 14 years

(Cl. D44—29)

To all whom it may concern:

Be it known that we, Bernard J. Zarzana and Roy T. Turner, citizens of the United States and residents of Whittier, county of Los Angeles, State of California, have invented a new, original, and ornamental Design for a Glass Rack, of which the following is a specification, reference being had to the accompanying drawing, forming a part hereof, in which:

Fig. 1 is a perspective view of a glass rack showing our new design;

Fig. 2 is a top plan view thereof;

Fig. 3 is a front elevational view thereof;

Fig. 4 is a bottom plan view thereof; and

Fig. 5 is an end elevational view thereof.

We claim:

The ornamental design for a glass rack, substantially as shown.

BERNARD J. ZARZANA.
ROY T. TURNER.
